GREGORY B. WEBB, OF BROOKLYN, NEW YORK, AND ERIC GILZEAN, OF KEARNY, NEW JERSEY.

COLLAPSIBLE FORM FOR CONCRETE CRYPTS.

Application filed August 3, 1926. Serial No. 126,831.

This invention relates to a collapsible form for casting concrete burial crypts and more particularly to such a form which is economical in construction and which can be easily set to pour the concrete and easily collapsed and removed by withdrawing the lower members of the two collapsible side walls of the form.

One of the objects of the invention is to provide a collapsible form for casting concrete burial crypts in which the form, after the concrete has been poured in to form the crypt, is surrounded by the concrete and in which, after the concrete has set, the side pieces of the form may be collapsed, thus permitting the collapsing and withdrawing of the form without injuring the concrete of the crypt, or the form.

Another object of the invention is to provide such a collapsible form that can be readily and conveniently used for casting a series of concrete crypts in rows and tiers, the form having an open bottom and its sides resting on the floor of concrete forming the roof of the tier previously cast.

Another object of the invention is to provide such a form, the two side walls each consisting of two side pieces, the upper side piece provided with transverse battens and meeting the lower side piece at an inclined angle so that the lower side piece may be withdrawn from beneath the upper piece, dropping the feet of the battens of the upper piece, to the supporting floor and collapsing the form.

With the above and other objects in view, the invention consists in the parts, improvements and combinations more fully pointed out hereinafter.

Referring now to the drawings:

Figure 1, is a vertical, longitudinal section showing the collapsible form resting on the top of a previously cast crypt, with the concrete poured around it.

Figure 2, is a longitudinal, transverse section on line 2—2 of Figure 1.

Figure 3, is a detail showing the assembled open spacing frame placed at the bottom of the form for holding the sides apart while the concrete is being poured.

Figure 4, is a detail view showing one of the two part sides.

Figure 5, is a detailed cross-sectional view, showing the means for hooking together a

side and the back of the form during the 55 assembling operation.

Figure 6, is a cross-sectional detail, illustrating the portions of the form used for casting the post.

Figure 7, is a detail longitudinal section 60 showing one corner of the form.

Figures 8 and 9, illustrate longitudinal vertical and transverse cross-sections showing the form when constructed for the casting of crypts without the end post. 65

Figure 10, is a transverse, cross-sectional view showing a row of crypts being cast with a form in place.

Figure 11 is a perspective view showing a form in use in casting one of a row of crypts. 70

Turning now to the drawings, the collapsible form includes a pair of sides, each side including two longitudinal side pieces 1, 2. The upper side pieces are provided with a series of transverse battens 3, and the lower 75 side pieces with a series of transverse battens 4. Both sets of battens cooperate and act as stops to limit the relative longitudinal movement of the upper and lower side pieces when the lower side pieces are pushed home 80 and when they are pulled out. The meeting edges of the upper and lower side pieces are longitudinally inclined so that the upper piece meets the lower piece at an acute angle. As will more fully appear below, this 85 will permit the upper piece to drop, when the lower side piece is pulled out by handle 7, so that the feet of the upper battens 3, will drop downward and rest upon the roof of the crypt below. The transverse collapsing of the side pieces thus lowers the top of the form and enables the form to be collapsed.

The top of the form preferably consists of two removable top sections 8 and 9, which 95 rest upon the tops of the upper side pieces and upon the detachable back 10 of the form. The back and the sides are preferably chamfered at their meeting edges 10^a, so as to form a close joint between the back and 100 sides and facilitate the withdrawal of the side pieces when the form is to be collapsed.

Each top section is provided with a plurality of cross pieces 11, which serve as struts between the side pieces, resisting the collapsing of the form when the concrete is poured and stamped, these cross pieces resting on top of the battens 3. The rear cross

pieces serve as stops for the top sections when the top sections are slipped in place upon the back and sides, the cross pieces abutting against strips 10^b secured to the 5 back 10. The top sections extend beyond the front of the crypt at 12, these portions serving as handles when the top sections are removed and receiving a stringer 13 and 10 slat 14, the slat limiting the flow of concrete and the stringer spacing the forms a predetermined distance apart by being nailed to the front portions of the top sections.

The top sections are supported at their 15 meeting edges by means of a longitudinal beam 15, which, in turn, is supported at the ends and an intermediate point. The back end of the beam rests in a pocket formed on the back 10 by a strip 16 and the intermediate portion and front end of the beam 20 are supported by vertical posts 17, 18, with cleats 18^a, nailed to their tops between which cleats the beam rests. The vertical posts rest upon wedges 19, 20 which may be knocked out when removing the beam and 25 collapsing the form.

An open spacing frame is provided which 30 includes a pair of longitudinal strips 21, 22, grooved at 23. The strips are placed on lateral struts 24 and the struts are each provided with a pair of top blocks 25, so as to hold the strips 21, 22 apart and firmly in place. Feet 26 may be provided for the struts to keep the frame off the concrete 35 floor.

35 This open frame provides a means for spacing the lower portions of the form and helps to prevent the lower side pieces from being forced together when the concrete is 40 poured and tamped between adjacent forms. The back and the top cross pieces 11, also help to maintain the form in its assembled 45 position and to prevent the collapsing of the form when the concrete is poured.

After the form has been assembled, the 45 workman, who can enter the form, may hook the parts together by means of hooks 27, which connect the adjacent top sections, hooks 28, which connect the back and sides, hooks 29, which connect the back and top 50 sections and hooks 30, which connect the sides and the top sections at the front of the form.

Boarding 31, supported by braces 32, is 55 provided which limits the flow of concrete and determines the thickness of the back wall of the crypt.

When casting an enlarged post at the end 60 of the side wall between adjacent crypts, as shown in Figure 6, the end of each side of the form is provided with a lateral block 33, having an inclined face 34, against which a side of the post is cast. An auxiliary form 65 35, is provided on the side of which is mounted a strip 36, with a wedge-shaped 35 projection, thus producing a groove in the

post. The door 37, for the completed crypt may be mounted in the end of the post and cement poured in between the door and the post, so as to fill the groove, after the crypt is occupied. A vertical strip 38, held in 70 place by stringer 39, is provided to form the front face of the post.

When casting the crypts without the enlarged front post as shown in Figure 9, auxiliary forms 35, are provided together with 75 a front strip 38, but the lateral block 33 is omitted.

Having thus described the construction, the operation of taking down the form will be clear. The form having been assembled 80 and the hooks used to connect the parts, the longitudinal beam and its supports having been inserted to support the meeting edges of the top sections, the open spacing frame with its lateral struts having been placed 85 in position and the boarding having been placed about the outside of the form and spaced therefrom, concrete is poured about the form and tamped down between the adjacent forms. After the concrete has set, the stringers and outside pieces are removed 90 and the form is collapsed by first unhooking the various hooks, then taking down the posts by knocking out the wedges underneath and removing the longitudinal beam supported thereby and then loosening the spacing frame as by tilting either of its sides upwardly and then removing it. Each lower side piece is then pulled forward, when casting the crypt without a front post as 95 shown in Figure 9, which permits the upper side pieces to drop so that the feet of their battens rest upon the concrete floor. This action will release the top sections so that the top sections and side pieces can be taken 100 out. After their removal the back can be taken out. When casting the post form of crypt, shown in Figure 6, the handle end of the lower side piece is first sprung laterally 105 inwardly, so as to clear the post, and then pulled forward so as to allow the upper side piece to drop down.

Having thus described the construction and operation, it will be understood that changes may be made in carrying the invention into effect, without departing from the principle of the invention.

What we claim is:

1. A collapsible form for casting concrete 120 burial crypts comprising in combination, a pair of collapsible sides, each including, at least two pieces having longitudinally inclined meeting edges, one of which is longitudinally movable with respect to the other and a removable top normally resting 125 on the longitudinal tops of the sides.

2. A collapsible form for casting concrete 130 burial crypts comprising in combination, a pair of transversely collapsible sides, each side having at least two longitudinal side

- pieces having longitudinally inclined meeting edges, the upper side piece being transversely movable and having transverse battens extending beyond the meeting edges 5 whose feet normally extend to a point above the floor of the crypts and the lower side pieces being longitudinally movable with respect to the upper side piece to collapse the form.
10. 3. A collapsible form for casting concrete burial crypts comprising in combination, a pair of transversely collapsible sides, a removable top, and a detachable back, each side including two longitudinal side pieces, the upper and lower side pieces having longitudinally inclined meeting edges.
4. A collapsible form for casting concrete burial crypts comprising in combination, a pair of transversely collapsible sides, a removable top and a detachable back, each side including two longitudinal side pieces, the upper and lower side pieces having inclined meeting edges, each upper and lower side piece being provided with a plurality of co-25 operating, transverse battens.
5. A collapsible form for casting concrete burial crypts comprising in combination, a pair of transversely collapsible sides, each having at least two longitudinal pieces having longitudinally inclined meeting edges, one of which is adapted to be moved longitudinally with relation to another, a removable top and a detachable back, said back and sides being connected together by re-30 leaseable hooks.
6. A collapsible form for casting concrete burial crypts comprising in combination, a pair of transversely collapsible sides, a two part collapsible top, a back, a longitudinal beam extending underneath the meeting edges of the two parts of the top and removable posts for supporting the said beam.
7. A collapsible form for casting concrete burial crypts comprising in combination, a pair of transversely collapsible sides, a two part collapsible top, a longitudinal beam extending underneath the meeting edges of the two parts of the top, removable posts for supporting said beam, and a back, the back being provided with a pocket to receive one end of said beam.
8. A collapsible form for casting concrete burial crypts comprising in combination, a pair of transversely collapsible sides having longitudinally inclined meeting edges, a removable top, a detachable back, a removable spacing frame arranged between the bottoms of said side pieces, said frame comprising two longitudinal strips adapted to contact with said side pieces and a plurality of lateral struts on which said longitudinal strips are supported.
9. A collapsible form for casting concrete burial crypts comprising in combination, a pair of transversely collapsible sides having longitudinally inclined meeting edges, a removable top, a detachable back, a removable open spacing frame arranged between the bottoms of said side pieces, said frame comprising two removable longitudinal strips adapted to contact with said side pieces and a plurality of lateral struts on which said longitudinal strips are supported, each of said struts, having two stops for limiting the inward movement of the longitudinal strips.
10. A collapsible form for casting concrete burial crypts comprising in combination, a pair of collapsible sides, a two part top, a back and a pair of auxiliary forms, each provided with a projecting portion and arranged adjacent to the projecting ends of the sides, for forming door grooves in the crypt wall ends.
11. A collapsible form for casting concrete burial crypts comprising in combination, a pair of transversely collapsible sides having longitudinally inclined meeting edges, a two part collapsible top and a detachable back, each part of the top being provided with cross pieces which abut against the sides and serve as struts.
12. A collapsible form for casting concrete burial crypts comprising in combination, a pair of collapsible sides, each side being formed of two sections with inclined meeting edges, the front of each section being provided with a lateral block, a two part top, a back and a pair of auxiliary forms, each provided with a projecting portion and arranged adjacent to the said lateral blocks, the form being thereby constructed to cast crypts with an enlarged front post at the end of the crypt wall.

In testimony whereof, we have signed our names to this specification.

GREGORY B. WEBB.
ERIC GILZEAN.
